UNITED STATES PATENT OFFICE.

GEORGE R. WAGNER, OF NEW YORK, N. Y., ASSIGNOR OF ONE-FOURTH TO HENRY JENKINS, OF WEST HOBOKEN, NEW JERSEY, AND ONE-FOURTH TO W. H. RANDALL AND ONE-FOURTH TO C. FRANK SHEPARD, BOTH OF BROOKLYN, NEW YORK.

ATTACHMENT FOR LINOTYPE-MACHINES.

1,186,958.

Specification of Letters Patent. Patented June 13, 1916.

Application filed December 29, 1914. Serial No. 878,437.

To all whom it may concern:

Be it known that I, GEORGE R. WAGNER, a citizen of the United States of America, and a resident of New York, county and State of New York, have invented certain new and useful Improvements in Attachments for Linotype-Machines, of which the following is a specification, reference being had to the accompanying drawings, forming a part thereof.

My invention relates to the manufacture of metal wedges such as are used by printers and are commonly known as "quoins."

Metal wedges or quoins are employed in pairs by printers for clamping columns of type on galleys. These wedges are used in large quantities and have hitherto been produced at considerable expense by pouring molten metal into molds, by hand, and finishing the wedge surfaces by filing, many of the wedges being so imperfect that they could not be used.

It has been my aim to provide a mold attachment for linotype or like type-setting machines, by means of which perfectly finished quoins may be readily and quickly made at small cost.

Another object of my invention is to provide a simple and improved mold for type-setting machines, particularly adapted for relatively heavy work, embodying simple and effective means for preventing the casting from being drawn back while it is being sheared off by the cutter.

Other objects and advantages of my invention will be set forth hereinafter, and in order that my invention may be thoroughly understood, I will now describe the same in the following specification and then point out the novel features thereof in appended claims.

Referring to the drawings: Figure 1 is a partial elevation of a mold wheel to which my invention is applied. Fig. 2 is a sectional elevation through the mold wheel showing the mouth of the melting pot and the elevator on opposite sides of the wheel in position for casting. An elevation of a portion of the matrix is shown in Fig. 3.

Fig. 4 is a partial elevation of the mold drawn to a larger scale and looking toward the matrix. A perspective view of one of the quoins is shown in Fig. 5.

While I have illustrated my invention as

applied to the manufacture of quoins, it is not limited in this field of usefulness and may be employed for heavy slugs of various kinds.

10 represents a mold wheel, 11 the mouth and throat of a linotype pot, and 12 an elevator, all of a well known design.

The mold of my invention is shown at 15, and has a flange 16 so that it is adapted to fit into the mold wheel as shown in Fig. 2. It is removably secured in place by screws 17 or other suitable means.

The mold has a slot 18 which extends through the body of the mold and has the form of the exterior of the quoin which is to be cast. Set in the mold flush with one of its surfaces 19 adjacent to the linotype pot, is a strip or bar 20 which extends across the slot 18, but is sufficiently narrow so as not to materially obstruct the opening. It is firmly set in the mold and forms a part of it.

A matrix 21 which is adapted to be mounted on the elevator 12 in a well known manner, has a core projection 22 which extends into the slot 18 in the mold and serves to lighten the quoins by materially reducing the volume of the die, comprising the mold and matrix, into which the molten metal is forced from the pot.

Both the mold and the matrix are detachably secured in position and may be easily and quickly mounted in a linotype machine of well known construction. When so mounted, quoins may be quickly produced in the type-setting machine by the usual type-setting process.

Quoins produced in this manner have the advantage of being substantially perfect and finished as they come from the machine and consequently the labor of filing or finishing as well as the loss due to imperfect castings, is avoided.

Assuming that the parts occupy the positions in which they are shown in Fig. 2, if the plunger of the linotype pot is then actuated to force molten metal into the die, a quoin will be cast as shown in the same figure. The strip or bar 20 is placed in a position to securely hold the quoin while the metal is being sheared off, in a well known manner, by the cutter. It nevertheless does not in any way interfere with the operation of the cutter nor with the ready removal of

the quoin from the mold. Furthermore, as clearly shown in Fig. 2, it is offset from, and substantially parallel to, the mouth opening of the melting pot so that it does not obstruct the opening or interfere with the free movement of molten metal into the die.

Modifications may obviously be effected within the spirit and scope of my invention, 10 and I intend that only such limitations be imposed as are indicated in the appended claims.

What I claim is:

1. A quoin molding machine comprising a support, a mold block secured thereto, the thickness of the mold block being the same as the desired height of the quoin and being constructed with a slot extending through it, shaped to produce the tapering walls of 15 the quoin, a melting pot having a narrow discharge passage opening into said slot, a member, a core member secured thereto having a core projection of less area than that of the tapering slot of the mold and a strip 20 extending through the slot to prevent the drawing out of the casting when the support is actuated.
2. A quoin molding machine comprising

a support, a mold block removably secured thereto, the thickness of the mold block being the same as the desired height of the quoin and being constructed with a slot extending through it, shaped to produce the tapering walls of the quoin, a melting pot having a narrow discharge passage opening 30 into said slot on one side of the block, a member, a core member removably secured to said member having a core projection of less area than that of the tapering slot of the mold adapted to extend into the slot 35 from the opposite side of the block, and a strip affixed in the mold block at the surface which is adjacent to the mouth of the melting pot and extending through the mold slot substantially parallel to the mouth of 40 the pot and offset therefrom to leave the mouth opening unobstructed and to prevent the drawing out of the casting when the support is actuated.

In testimony whereof I have hereunto set 50 my hand this 12th day of December 1914, in the presence of two subscribing witnesses.

GEORGE R. WAGNER.
